UNITED STATES PATENT OFFICE.

THOMAS J. BROWNING, OF WAYNESBORO, MISSISSIPPI.

GATE-LATCH.

1,090,969.

Specification of Letters Patent. Patented Mar. 24, 1914.

Application filed November 5, 1913. Serial No. 799,372.

To all whom it may concern:

Be it known that I, THOMAS J. BROWNING, a citizen of the United States, residing at Waynesboro, in the county of Wayne and 5 State of Mississippi, have invented a new and useful Gate-Latch, of which the following is a specification.

The present invention appertains to a latch for gates, and doors, and contemplates 10 the provision of a novel and improved device of that character.

Another object of the present invention is to provide means whereby the keeper ring and latch bar may be locked together by 15 means of a padlock.

With the foregoing and other objects in view which will appear as the description proceeds, the invention resides in the combination and arrangement of parts and in the 20 details of construction hereinafter described and claimed, it being understood that changes in the precise embodiment of the invention herein disclosed, can be made within the scope of what is claimed, without departing from the spirit of the invention.

The invention has been illustrated in its preferred embodiment in the accompanying drawing, wherein:—

Figure 1 is a perspective view of the latch 30 mechanism applied to a gate and post. Fig. 2 is a sectional detail of the gate and post, taken above the latch mechanism. Fig. 3 is a sectional view taken on the line 3—3 of Fig. 2.

In the drawing, the numeral 1 designates a gate, although the same may be taken as typical, to represent a door or other movable structures, and the numeral 2 designates the fence post adjoining the free end of the 40 gate, which may also be taken as typical.

In carrying out the present invention, there is provided a keeper ring 3, which is mounted within the arms of a U-shaped carrier or holder 4, which carrier is preferably 45 bent from a bar or strip of metal. One end portion 5 of the carrier 4 is straight, and is adapted to be secured to that side of the post 2 adjoining the free end of the gate 1, while the other end portion 6 of the carrier 4 is 50 bent angularly, to be secured to the adjoining side of the post whereby the intermediate portion or body of the carrier 4 will be effectively disposed for cooperation with the free end of the gate. The keeper ring 3

is disposed between the arms of the carrier 55 4 and intermediate of the bend of the carrier, and the end portions 5—6, a rivet or pin 7 being secured through the arms of the carrier to support the keeper ring for free movements about the rivet or pin. Particular attention is directed to the fact that the rivet 7 is disposed relatively close to the bend of the carrier, and to the lower edges 60 of the carrier arms, in order that the keeper ring will operate to carry out certain desired results, as will hereinafter more fully appear.

A latch bar 8 is secured to the gate 1, and is preferably rigid with the gate, with its free end projecting or protruding for engagement with the keeper ring 3 below the carrier 4, the latch bar 8 having an outstanding ear or lobe 9, so arranged as to project along the lower portion of the keeper ring when the latch bar is engaged by the 75 said ring, and the said ear being apertured, whereby a padlock may be engaged to the said ear and lower portion of the keeper ring, as seen in Fig. 3. The latch bar 8 is so arranged, as to swing snugly under the 80 carrier 4 whereby when the gate is closed, the free end of the latch bar engaging the keeper ring, will throw the keeper ring upwardly, and when the free end of the latch bar strikes the post 2, the keeper ring will 85 drop, to lock between the latch bar, and the bend of the carrier 4. Thus, the gate will be effectively locked, and it will not be possible to force the keeper ring 3 upwardly, by pressure against the gate, the rivet 7 being so disposed as not to permit the keeper ring to be forced upwardly by the outward movement of the gate. The rivet 7, however, permits the keeper ring to readily swing upward when the gate is closed. To 90

lock the gate, the shackle of the padlock 10 may be readily engaged through the apertured ear 9 and the lower portion of the keeper ring 3, which will prevent the keeper ring from being disengaged from the latch 100 bar until the lock is removed.

From the foregoing, taken in connection with the drawing, the advantages and capabilities of the present device will be obvious to those versed in the art, and need 105 not be commented upon at length, it being obvious that the objects aimed at have been carried out in a satisfactory manner.

Having thus described the invention, what is claimed as new is:

In combination with parts movable to and from each other, a carrier attached to one part, a keeper ring loosely supported by the carrier, and a latch bar attached to the other part to move snugly under the carrier for the engagement of the keeper ring, the latch bar having an apertured ear so arranged as to project along the lower portion of the keeper ring when the latch bar is engaged

by the keeper ring, said apertured ear and keeper ring being adapted to be engaged by a padlock.

In testimony that I claim the foregoing 15 as my own, I have hereto affixed my signature in the presence of two witnesses.

T. J. BROWNING.
